UNITED STATES PATENT OFFICE.

EDWARD BLOUNT, OF QUITMAN, GEORGIA, ASSIGNOR TO THE BLOUNT TURPENTINE TOOL COMPANY, OF SAME PLACE.

BARREL ATTACHMENT.

SPECIFICATION forming part of Letters Patent No. 554,211, dated February 4, 1896.

Application filed July 29, 1895. Serial No. 557,448. (No model.)

To all whom it may concern:

Be it known that I, EDWARD BLOUNT, a citizen of the United States, residing at Quitman, in the county of Brooks and State of Georgia, have invented a new and useful Barrel Attachment, of which the following is a specification.

This invention relates to barrel attachments; and it has for its object to provide a new and useful scuttle-head attachment for barrels that is particularly designed to be used in connection with turpentine-dip barrels after the original head thereof has been removed.

15 To this end, therefore, the main and primary object of the present invention is to provide a scuttle-head attachment for barrels that will give the largest possible opening or scuttle for the contents of the barrel to flow 20 out of, while at the same time strengthening and reinforcing the open end of the barrel from which the original head has been removed.

Furthermore, the invention also provides 25 means whereby when used in connection with a turpentine-barrel the gum can be put into the barrel easily and readily by the dipper, while at the same time providing means for 30 easily and securely fastening the removable cover or head in position within the open end of the barrel when the same is filled.

With these and other objects in view, which will readily appear as the nature of the invention is better understood, the same consists in the novel construction, combination, 35 and arrangement of parts hereinafter more fully described, illustrated, and claimed.

In the drawings, Figure 1 is a sectional view of the upper part of a turpentine-barrel 40 equipped with the herein-described improvement. Fig. 2 is a detail in perspective of the ring-plate removed from the barrel. Fig. 3 is a bottom plan view of the removable cover 45 preferably employed in connection with the ring-plate.

Referring to the accompanying drawings, 1 designates an ordinary barrel, preferably of that character employed for transporting the crude gum to the distillery, and said barrel 50 is provided with the usual croze 2, in which the edges of the original head fitted, and in

the present invention the position occupied by the original head of the barrel is adapted to be occupied by the stationary ring-plate 3. The stationary ring-plate 3 is provided with 55 a double-beveled outer edge 4 that snugly registers in the croze 2 of the barrel, and by tightening the hoops of the barrel after the said ring-plate has been fitted in position the same will be held firmly in place so as to form 60 a rigid base or support for the removable cover, to be referred to, and it will also be observed that by reason of employing the ring-plate 3 the largest possible opening or scuttle is provided for that end of the barrel 65 from which the crude turpentine-gum is flowed in emptying the barrel, while at the same time the said ring-plate strengthens and reinforces the barrel at the point where it is located, as will be obvious. The said ring- 70 plate 3 is provided upon its under side at diametrically-opposite points of its inner edge with the flat lug portions 5, and upon its upper side adjacent to its inner edge the said ring-plate is provided with a pointed ridge 6, 75 that is adapted to fit in a similarly-shaped circular groove 7, formed in the under side of the removable cover 8, that is adapted to be placed directly on top of the ring-plate to form a closure for the barrel. The said removable cover 8 is provided with a central opening 9, in which loosely works the ring-bolt 10, the inner threaded end of which engages in the threaded opening 11 of the nut- 80 plate 12, fastened to the under side of the 85 lock-bar 13. The lock-bar 13 is provided near one end with a pin-opening 14, that loosely receives a fixed pin 15, projected from the lower side of the cover and serving to hold the lock-bar 13 against turning, so that the 90 ring-bolt can be screwed and unscrewed in said nut-plate.

By unscrewing the ring-bolt 10 the lock-bar 13 may be allowed to lower away from the lower side of the cover sufficiently so that 95 the opposite ends of said lock-bar can be engaged under and disengaged from under the inner edge of the ring-plate 3, and in placing the cover in position after the ends of the lock-bar have been engaged under the inner 100 edge of the ring-plate at diametrically-opposite points by screwing up the ring-bolt the

- lock-bar will be clamped tight against the under side of the ring-plate to securely lock the cover in position, and as thus arranged the ends of the lock-bar are preferably held 5 against the opposite flat lug portions 5 of the ring-plate. When the cover is in position on the ring-plate the ridge 6 and groove 7 insure a liquid-tight joint and complete a tight closure for the barrel.
- 10 Other means than those described for locking the cover onto the ring-plate may be employed, and other changes in the form, proportion, and the minor details of construction may be resorted to without departing from the principle or sacrificing any of the advantages of this invention.
- Having thus described the invention, what is claimed, and desired to be secured by Letters Patent, is—
- 15
- 20 In a barrel attachment, the combination of a ring-plate provided with a beveled outer edge adapted to engage in the croze of a barrel, a circular pointed ridge projected from its

upper side and near its inner edge, and flat lug portions on its under side at diametrically-opposite points of its inner edge, a cover provided in its under side with a circular groove registering with the ridge of said plate, and with a depending fixed pin, a lock-bar arranged under the cover and provided with 25 a central nut-plate and with a pin-opening loosely receiving said fixed pin, the opposite extremities of said lock-bar being adapted to rest directly on the flat lug portions of said ring-plate, and an adjusting-bolt loosely mounted in the cover and having its threads 30 engaging the threads of said nut-plate, substantially as set forth.

In testimony that I claim the foregoing as my own I have hereto affixed my signature in 40 the presence of two witnesses.

EDWARD BLOUNT.
